STOKER FURNACE

Joseph S. Bennett, Merion, Pa., assignor to American Engineering Company, Philadelphia, Pa., a corporation of Pennsylvania

Application November 2, 1946, Serial No. 707,425

3 Claims. (Cl. 122—235)

1

This invention relates to stoker furnaces, and more particularly to stoker furnaces adapted for installation in power plants employing large, high capacity boilers.

In order to obtain maximum capacities and efficiencies in steam power plants, it is necessary that the entire grate area of the furnace be effectively utilized to burn the fuel supplied thereto. One of the problems encountered in stokers employed in the larger installations is in effectively feeding and distributing fuel so that the entire available grate surface will be utilized effectively. In many of the modern power plants the boilers installed are of considerable depth from front to rear of the furnace. In such furnaces it has been found that the fuel feeding devices of the stokers heretofore employed were inadequate to feed and distribute the fuel in such a manner that the required capacities and efficiencies thereof could be obtained. This has been found to be true regardless of the type of stokers employed, since feeding fuel over relatively long distances introduces many problems both in connection with the fuel feeding and distributing mechanism employed and due to slag and clinker formations which greatly impair proper operation of the furnace.

One object of the present invention is to provide novel furnace constructions which eliminate the various problems heretofore encountered and which enable operation of the furnace at the maximum capacities and efficiencies.

Another object is to provide a novel furnace wherein feeding of the fuel is effected at the side thereof rather than at the front or rear of the furnace as is usually the case.

A further object is to provide a novel furnace construction wherein sectionalized stoker units may be utilized to fire the associated boiler rather than a single stoker unit as was done heretofore.

A still further object is to provide a new and improved boiler furnace of high capacity employing sectionalized stoker units to fire the associated boiler and wherein feeding and distributing of fuel to said stoker unit is effected through one or both of the side walls of said furnace.

A still further object is to provide in stoker furnaces of the character described water-cooled screens between the various stoker units, the tubes of the said water-cooled screens being so arranged as to facilitate the passage of combustion gases therebetween.

A still further object is to provide in furnaces of the character described one or more stoker units of the traveling grate spreader type.

2

Other and further objects will become apparent as the description of the invention progresses.

Of the drawings:

Fig. 1 is a longitudinal sectional elevational view of the furnace, showing the arrangement of the various elements thereof.

Fig. 2 is a transverse sectional elevational view taken substantially along line 2—2 of Fig. 1.

Fig. 3 is a plan view, partly in section, taken substantially along line 3—3 of Fig. 2.

Fig. 4 is a sectional view of the tubes of a portion of one of the water-cooled screens taken substantially along line 4—4 of Fig. 1.

Fig. 5 is a transverse sectional elevational view of a furnace of an alternative construction.

Fig. 6 is a plan view, partly in section, taken substantially along line 6—6 of Fig. 5.

Fig. 7 is a sectional view of the tubes of a portion of one of the water-cooled screens taken substantially along line 7—7 of Fig. 5.

Referring to the drawings, and more particularly to Figs. 1 to 3 thereof, the numeral 1 designates generally a furnace comprising front and rear walls 2 and 3 respectively and side walls 4 and 5. Extending between side walls 4 and 5 and forming the bottom wall of the combustion chamber 6 of the furnace are three units 7, 8 and 9 of a stoker indicated generally at 10.

Mounted in any suitable manner in combustion chamber 6 is a boiler 11. Boiler 11 may be of any suitable type and, as illustrated, comprises three steam drums 12, 13 and 14 and a mud drum 15. Banks of tubes 16, 17 and 18, of usual construction, extend between and are connected to steam drums 12, 13 and 14 respectively and mud drum 15. Banks of tubes 19 and 20 also connect steam drums 12 and 14 to steam drum 13. A lower baffle 21 and an upper baffle 21^a, extending respectively from the rear and front ends of the combustion chamber transversely over the stoker sections direct the flow of combustion gases from the stoker sections to and over a common path traversing the drums and tubes of the boiler. Baffles 21^a, 21^b and 21^c of usual construction, 40 compel the furnace gases to follow the direction of the arrows in Figs. 1 to the lower end of an economizer mounted adjacent rear wall 3 and indicated generally by numeral 25. The furnace gases flow upwardly in economizer 25 and into duct 26 connected to the inlet side of an induction fan 27 from which the gases are conducted to the stack 28 of the furnace by an outlet duct 29. Fan 27 and duct 26 are mounted on any suitable supporting structure 30 disposed a short distance beneath the roof 31 of the furnace 1.

50

Fan 27 may be operated by any suitable power means, such as by an electric motor 27a.

Air for combustion purposes is forced through economizer 25 by a fan or blower 32 mounted on any suitable support 33 provided above duct 26. The heated air emerges from economizer 25 through a duct 34 connected at the upper end thereof to said economizer and at the lower end to one end of a communicating duct 35 mounted in any suitable manner adjacent to and near the lower end of side wall 5. Branch ducts 36, 37 and 38 connect communicating duct 35 with plenum chambers 39, 40 and 41 provided respectively beneath stoker units 7, 8 and 9.

The lower portion 43 of baffle 21 is spaced a short distance from mud drum 15. As a result any cinders or fly ash settling on mud drum 15 will pass between the tubes of bank 16 and onto a deflector plate 44. Deflector plate 44 conducts the cinders and fly ash to a hopper 45 provided adjacent the lower end of economizer 25. A valve 46 is provided at the lower end of hopper 45 through which the cinders and fly ash may pass to a second hopper 45a disposed therebeneath. A second hopper 47 is connected to the lower end of economizer 25 for receiving any cinders or fly ash settling in the latter as the furnace gases flow therethrough. A valve 48 is provided at the lower end of hopper 47 through which the cinders and fly ash collecting in said hopper may pass to a second hopper 47a. Hoppers 45a and 47a are connected to any suitable blower, indicated at 49, having a spout 49a connected to the discharge side thereof. The cinders and fly ash delivered to spout 49a by blower 49 are conducted thereby to any suitable place of disposal. A sealing plate 44a extends between mud drum 15 and the lower end of economizer 25 to prevent the flow of gases from the latter into hopper 45.

Each of the stoker units 7, 8 and 9 is similar in construction, and is generally similar to the stoker shown and described in the pending application of June E. Beck and Ernst L. Midgette, Serial No. 644,580, filed January 31, 1946, now Patent No. 2,531,779, and to which reference may be had for a complete disclosure thereof. Inasmuch as the stoker units 7, 8 and 9 are similar in construction a description of one will suffice for all. For convenience, a description will be given of stoker unit 7, and upon reference to Figs. 1 and 2 it will be observed that said stoker unit comprises an endless traveling grate 50, which is mounted upon a supporting framework 51. Traveling grate 50, as shown herein, is comprised of two sections 50a and 50b, disposed in side by side relation, although it is apparent that a greater or lesser number of such sections may be provided, if so desired, without departing from the invention. Framework 51 comprises a series of I-beams 52 extending lengthwise of the grate 50 which in turn are mounted upon a series of transverse I-beams 53. The transverse I-beams 53 for stoker units 7 and 9 may be supported at the outer ends thereof on transverse I-beams 53a and 53b mounted adjacent front and rear walls 2 and 3 respectively and at their inner ends on supporting structures indicated generally at 53c and 53d. The transverse I-beams 53 for stoker unit 8 are supported at the opposite ends thereof on supporting structures indicated generally at 53e and 53f.

Sprocket wheels 54 and 55 are secured to shafts 56 and 57 respectively, which are mounted in any suitable bearings provided near the outer ends

of framework 51. Chains (not shown), to which the grate bars 58 of grate 50 are pivotally attached, are trained over sprocket wheels 54 and 55. Shaft 57 is actuated by any suitable operating mechanism, such as that shown in the pending application, Serial No. 644,580, previously referred to herein.

The right hand end (Fig. 2) of stoker unit 7 extends into an enclosure 60 mounted exteriorly of side wall 4. Suitable access doors 61 are provided in enclosure 60 to enable the operator to observe the fire and otherwise tend to the stoker. The lower end 62 of side wall 4 is spaced from grate 50 to enable movement of the grate and the fuel or ashes thereon past said wall. In operation, shaft 57 is so operated as to cause the upper run 63 of grate 50 to move from left to right (Fig. 2). The ashes carried by grate 50 are dumped over the right hand end thereof (Fig. 2) and gravitate into an ash pocket 64 provided beneath the enclosure 60.

In order to prevent separation of the grate bars 58 as they pass over sprocket wheel 55, retaining shoes 65 are provided. As shown in Fig. 2, each shoe 65 is pivotally supported as the upper end of an arm 66 which in turn is rigidly connected to a rod 67 mounted in brackets 68 secured to the front end of a skid ramp 69. The grate bars 58 are also held in contact with each other as they pass over the inclined surface 70 of skid ramp 69.

Air for combustion purposes is supplied to plenum chamber 39 from ducts 35 and 36, as previously described. The air in chamber 39 passes upwardly between the grate bars 58 and into the combustion chamber 6 in the usual fashion. In order to prevent the escape of air beyond the intermediate extremities of stoker unit 7, suitable sealing means is provided. As shown in Fig. 2, a vertical sealing plate 72 forms one end wall of chamber 39. Plate 72 is curved at the upper end thereof so as to extend partially around the left hand end of stoker unit 7. An inclined plate 73 extends between the top of plate 72 and the inner surface 74 of side wall 5. A sealing plate 75 interlockingly engages the upper end of plate 72 and rests upon the upper surface of the grate bars 58. A second sealing plate 76 is provided beneath the grate bars 58 near the right hand end (Fig. 2) of stoker unit 7. A weighted lever 77 engages the underside of sealing plate 76 and resiliently retains the latter in engagement with the grate bars 58.

A hopper 78 is provided beneath stoker unit 7 for receiving the siftings passing between the grates 58 thereof. These siftings may be removed from time to time through a spout 80 connected to the lower end of hopper 78.

Fuel is fed to and distributed over grate 50 by rotors 81, 81. Rotors 81, 81 are rotatably mounted exteriorly of side wall 4 and propel the fuel through openings 82, 82 provided in said wall. Conveying mechanisms 83, 83 convey fuel from hoppers 84, 84 disposed thereabove to the rotors 81, 81, the said hoppers in turn receiving fuel from an overhead bunker 85 through communicating spouts 86, 86. Two fuel feeding and distributing rotors and associated apparatus are shown for each of the stoker units 7, 8 and 9. It is apparent, however, that a greater or lesser number of such rotors and associated apparatus may be provided for each stoker, if it is so desired, without departing from the invention.

The feeding and distributing rotors 81, 81 may be of any suitable type, such, for example, as 75 that shown and described in the pending appli-

cation of Ernst L. Midgette and Robert W. Reid, Serial No. 599,812, filed June 16, 1945, now Patent No. 2,511,935.

As shown more particularly in Figs. 1 and 3, a water-cooled screen 90 is provided between stoker units 7 and 8. Water-cooled screen 90 comprises a series of vertically disposed tubes 91 connected to and extending upwardly from a header 92 supported upon a resilient supporting member 93 provided between the lower end of header 92 and a transverse supporting I-beam 94. The lower portions 95 of tubes 91 lie in substantially the same plane and have protective blocks 96 and 97 provided respectively at opposite sides thereof. In order to facilitate the passage of furnace gases between stoker units 7 and 8, alternately disposed tubes 91^a and 91^b are bent slightly to the left and right (Fig. 1) respectively, as shown at 98 and 99. The tubes then continue upwardly in substantially parallel relation, and are then bent forwardly and upwardly as shown at 101 and 102. The tubes are then bent rearwardly and upwardly as shown at 103 and 104, and the upper extremities 105 thereof then continue in substantially the same plane and terminate at their upper ends in steam drum 12. By providing a resilient support 93 for header 92, the water wall is free to expand and contract due to the changing temperature conditions in the furnace.

A second water-cooled screen 107 is provided between stoker units 8 and 9. Water-cooled screen 107 is generally similar in construction to water-cooled screen 90 and also comprises a series of vertically disposed tubes 108 extending upwardly from a header 109. Header 109 is mounted upon a resilient support 110, extending between the bottom of said header and a transverse supporting I-beam 111. The opposite sides of the lower portions 112 of tubes 108 are provided with protective blocks 113 and 114 as shown in Figs. 1 and 3. The alternately disposed tubes 108^a and 108^b of water-cooled screen 107 are bent to the left and to the right as shown at 115 and 116, and then extend vertically in substantially parallel relation. The alternately disposed tubes 108^a and 108^b are then bent upwardly and forwardly as shown at 117 and 118, and then are bent upwardly so as to extend in substantially the same plane as shown at 119 and 120, and terminate at their upper ends in steam drum 12. By separating the alternately disposed tubes in this manner movement of the furnace gases between the said tubes is facilitated.

A water wall 123 is provided adjacent the interior of front wall 2. Water wall 123 comprises a series of vertically disposed and parallelly arranged tubes 124, which are connected at their lower ends to a header 125. Header 125 is mounted upon a resilient supporting member 126 which in turn is mounted upon a transverse supporting I-beam 127. The upper ends of tubes 124 are bent rearwardly as shown at 128, and terminate at their upwardly and rearwardly disposed ends in steam drum 12.

A water wall 130 is also provided adjacent rear wall 3. Water wall 130 comprises a series of vertically disposed and parallelly arranged fluid conducting tubes 131, which are connected at their lower ends to a header 132. Header 132 is mounted upon a resilient supporting member 133 disposed between the lower end of said header and a transverse supporting I-beam 134. The upper ends of tubes 131 are bent forwardly and slightly upwardly as shown at 135, and then are

bent upwardly and rearwardly as shown at 136, and terminate at their upper ends in mud drum 15. Protective blocks 123^a and 130^a are also provided on the tubes 124 and 131 of water walls 123 and 130 respectively, as shown more particularly in Figs. 1 and 3.

Headers 92, 109, 125 and 132 are connected to the mud drum 15 of boiler 11 by downtake connections 92^a, 109^a, 125^a and 132^a. In view of the resilient supports provided for headers 125 and 132, front and rear water walls 123 and 130 are also free to expand and contract due to the changing temperature conditions in the furnace. During operation of the furnace, the furnace gases flow in the direction of the arrows shown in Fig. 1 and pass between the tubes of water-cooled screens 90 and 107, and thence flow through the boiler 11 around baffles 21, 21^a, 21^b and 21^c, and then enter the lower end of economizer 25. The gases then flow upwardly through economizer 25 and into duct 26, thence through induction fan 27, outlet duct 29 and into stack 28.

By arranging water-cooled screens 90 and 107 in the manner shown, a considerable quantity of the heat generated in the furnace is absorbed thereby, since they are disposed in the combustion chamber and lie in the hottest portions of the furnace.

Water walls 123 and 130 also absorb a considerable quantity of the heat generated and add materially to the steam generated in the system. The water-cooled screens 90 and 107 and water walls 123 and 130, together with the banks of tubes 16, 17 and 18 of boiler 11, constitute an efficient steam generating system, which operates at maximum efficiencies under all conditions of operation.

By dividing the stoker 10 into units 7, 8 and 9, as shown herein, effective firing of boilers of the largest types is assured. It is also seen that by dividing the stoker into units and operating them in the manner hereinbefore mentioned, efficient feeding distribution of the fuel may be obtained. Consequently, maximum efficiencies and capacities are assured.

The stoker units units 7, 8 and 9 may be operated by a common operating mechanism or a separate operating mechanism may be provided for each of the units, as desired, without departing from the invention.

Figs. 5 and 6 disclose an alternate construction wherein firing of the boiler is effected from both of the side walls of the furnace. As shown there-in numeral 142 designates a furnace comprising front and rear walls 143 and 144 respectively and side walls 145 and 146. A stoker 147 comprising units 148^a, 148^b, 149^a, 149^b and 150^a, 150^b is provided in the furnace and constitutes the bottom wall of the combustion chamber 151 thereof. The pairs of stoker units 148^a, 148^b, 149^a, 149^b and 150^a, 150^b are disposed in end to end relation, and all the units are generally similar in construction. The said stoker units are also generally similar in construction to the stoker units 7, 8 and 9 previously described. Accordingly, because of the similarity of the stoker units shown in Figs. 5 and 6, a description of one pair of such units will suffice for all, and for convenience a brief description will now be given of stoker units 148^a and 148^b.

Stoker unit 148^a comprises a traveling grate 152, consisting of a series of grate bars 153 mounted upon a supporting framework 154. Sprocket wheels 155 and 156, mounted respectively on

shafts 157 and 158 journalled in bearings provided near the opposite ends of framework 154, have trained thereover chains (not shown) to which the grate bars 153 are pivotally attached. The front end of stoker unit 148^a extends into an enclosure 160 disposed exteriorly of side wall 145. Shaft 158 is operatively connected to any suitable operating mechanism, such, for example, as that shown and described in the previously referred to pending application, Serial No. 599,812, and to which reference may be had for a full disclosure thereof.

Upon operation of shaft 158, the upper run 159 of grate 152 is caused to move from left to right (Fig. 5), causing the ashes carried thereby to be dumped over the right hand end of the stoker. The ashes so dumped gravitate into an ash pocket 162 disposed beneath enclosure 160, from which they may be removed from time to time by any suitable means.

The siftings passing between the grate bars 153 of stoker unit 148^a gravitate into a hopper 163 disposed beneath said stoker. A spout 164 is connected to the lower end of hopper 163, which conducts the siftings to any suitable place of disposal. Air for combustion purposes is supplied to the stoker unit 148^a by any suitable fan or blower mechanism (not shown), the said air being conducted to a plenum chamber 166, disposed beneath said stoker unit by means of a communicating duct 165 and a branch duct 167.

The left hand end (Fig. 5) of the plenum chamber 166 is bounded by an end plate 168, which is curved at the upper end thereof, as shown at 169, so as to extend around a portion of the left hand end of stoker unit 148^a.

A sealing plate 172 engages the upper end of end plate 168 and rests upon the grate bars 153 of traveling grate 152. Sealing plate 172 extends transversely of the stoker unit 148^a and may be attached to end plate 168 in any suitable manner. A second sealing plate 173 is provided beneath the grate 152, near the right hand end (Fig. 5) of stoker unit 148^a, and a weighted lever 174 retains the plate 173 in engagement with the said grate.

Fuel is fed and distributed over the grate 152 of the stoker unit 148^a through a pair of openings 175, 175 provided in side wall 145 by feeding rotors 176, 176. Fuel from hoppers 177, 177 is conducted to rotors 176, 176 by any suitable conveyor mechanisms 178, 178. Hoppers 177, 177 may be supplied with fuel from any suitable overhead bunkers (not shown) through spouts 179, 179.

Stoker unit 148^b is similar in construction to stoker unit 148^a, and also comprises a traveling grate 182 consisting of a series of grate bars 183 mounted upon a supporting framework 184. Sprocket wheels 185 and 186 mounted on shafts 187 and 188, journalled in any suitable bearings provided respectively near the opposite ends of framework 184, have chains (not shown) trained thereover, to which the grate bars 183 are pivotally attached. Shaft 188 is connected to any suitable operating mechanism (not shown), such as that disclosed in the previously referred to pending application, Serial No. 644,580.

The left hand end (Fig. 5) of stoker unit 148^b extends into an enclosure 189 disposed exteriorly of side wall 146. Shaft 188 is so operated by the operating mechanism that the upper run 192 of grate 182 is caused to move from right to left (Fig. 5) of the furnace, causing the ashes carried thereby to be dumped over the left hand end of the stoker unit and into an ash pocket 193 dis-

posed beneath the enclosure 189. Any siftings passing between the grate bars 183 of the grate 182 gravitate into a hopper 194 disposed beneath stoker unit 148^b. A spout 195 connected to the lower end of hopper 194 conducts the siftings collecting in hopper 194 to any suitable place of disposal.

Air for combustion is conducted to a plenum chamber 196, disposed beneath the stoker unit 148^b, by any fan or blower mechanism (not shown). As shown more particularly in Fig. 5, the air from the said fan or blower is conducted to plenum chamber 196 through a communicating duct 197 and a branch duct 198. Plenum chamber 196 is closed at one end thereof by an end plate 199, having a curved portion 202 at the upper end thereof, which partly surrounds the right hand end (Fig. 5) of stoker unit 148^b.

A sealing plate 203, extending transversely of stoker unit 148^b, rests upon the grate bars 183 as they pass around sprocket wheel 185. Sealing plate 203 may be attached to the upper end of plate 199 by any suitable means. A second sealing plate 204 is provided beneath the grate bars 183 of stoker unit 148^b, near the right hand end thereof, and is held in engagement with the said grate bars by means of a weighted lever 205.

Fuel is fed to and distributed over the grate 182 of stoker unit 148^b through openings 206, 206 provided in side wall 146 by feeding and distributing rotors 207, 207. Fuel from hoppers 208, 208 is conveyed to rotors 207, 207 by means of any suitable conveyor mechanisms, shown generally at 209, 209. Fuel is supplied to the hoppers 208, 208 from overhead bunkers (not shown) through the spouts 212, 212.

The upper ends of end plates 168 and 199 have extending upwardly and inwardly thereof plates 213 and 214, which have air openings 215 and 216 provided therein through which secondary air may enter the combustion chamber 151 above stoker units 148^a and 148^b. As shown more particularly in Fig. 5, end plates 168 and 199 are spaced apart to form a duct 217, which communicates with the communicating duct 197. Accordingly, a portion of the air from communicating duct 197 will flow upwardly into duct 217 and then emerge into combustion chamber 151 through openings 215 and 216 provided in plates 213 and 214 respectively.

A water-cooled screen 220 is provided between stoker units 148^a, 148^b and 149^a, 149^b. Water-cooled screen 220 comprises two rows of vertically disposed fluid conducting tubes 221 and 222. The lower ends of tubes 221 and 222 are connected to headers (not shown) mounted in any suitable manner beneath stoker 147. The lower portions of the opposite sides respectively of tubes 221 and 222 are covered by protective blocks 223 and 224, as shown in Figs. 5 and 6. The intermediate portions of alternately disposed tubes 221 and 222 are bent outwardly, as shown in Fig. 7, so as to facilitate the passage of furnace gases therebetween. The said tubes 221 and 222 then continue upwardly through combustion chamber 151 similarly to tubes 91 of water-cooled screen 90, previously described, and terminate at their upper ends in one of the steam drums of a boiler (not shown).

A second water-cooled screen 226 is disposed between stoker units 149^a, 149^b and 150^a, 150^b. Water-cooled screen 226 is similar in construction to water-cooled screen 220, and also comprises two rows of vertically extending fluid conducting tubes 227 and 228. Tubes 227 and 228

are connected at their lower ends to headers (not shown) disposed beneath stoker 147. The opposite sides of the lower portions of tubes 227 and 228 have provided thereon protective blocks 229 and 232 respectively. The tubes 227 and 228 extend upwardly through the combustion chamber 151 similarly to tubes 112 of water wall 108, and the portions disposed above the protective blocks 229 and 232 are bent outwardly similarly to the tubes 221 and 222, as shown in Fig. 7, so as to facilitate the passage of furnace gases therebetween. The tubes then continue upwardly similarly to the tubes 112 of water wall 108 and terminate at their upper ends in one of the steam drums of the boiler (not shown).

Front wall 143 also has provided interiorly thereof a water wall 233. Water wall 233 comprises a series of vertically disposed, parallelly arranged fluid conducting tubes 234, which are connected at their lower ends to a header (not shown), disposed beneath the stoker 147. The tubes 234 extend upwardly along wall 143 similarly to the tubes 124 of water wall 123, and are then bent inwardly, and also terminate in one of the steam drums of the boiler (not shown).

Rear wall 144 has also mounted interiorly thereof a water wall 236, consisting of a series of vertically disposed and parallelly arranged fluid conducting tubes 237, which are connected at their lower ends to a header (not shown) disposed beneath stoker 147. Water wall 236 is similar to the water wall 130 shown in Fig. 1 and the tubes thereof extend upwardly along the rear wall and are then bent forwardly and terminate at their upper ends in the mud drum of the boiler (not shown).

Water-cooled screens 220 and 226, as shown, are comprised of two rows of fluid conducting tubes. It is apparent, however, that water-cooled screens consisting of a greater or lesser number of rows of tubes may be provided, if it is so desired, without departing from the invention.

From the foregoing description it is seen that novel and highly efficient stoker furnaces have been provided, which are capable of operating at the highest efficiencies under all conditions of operation. The stoker furnaces herein shown and described are particularly adapted for use in connection with the larger boiler units, although they may be employed with equal efficiency in smaller units. By arranging the units as herein shown and described, the entire grate area of the furnace may be effectively utilized, and as a result the furnace may be operated efficiently at the highest capacities.

It is apparent that the constructions herein shown and described may be modified to meet the requirements of the different types of furnaces and boiler installations without departing from the invention. Accordingly, while the embodiments of the invention herein shown and described are admirably adapted to fulfill the objects primarily stated, it is to be understood that it is not intended to limit the invention thereto, since it may be embodied in other forms,

all coming within the scope of the claims which follow.

What is claimed is:

1. In a boiler furnace having front and rear end and side walls defining a combustion chamber, boiler drums extending transversely between said side walls, and boiler tubes in transverse banks connected to said drums and forming with the latter a boiler assembly above said chamber, stoker means forming the bottom wall of said combustion chamber and comprising a plurality of individual sections each extending endwise between said side walls and in side-by-side relation so that the fuel and ash move across the furnace, a fluid cooled screen in the form of an upwardly extending transversely disposed bank of fluid conducting tubes located between each adjoining pair of said stoker sections and connected to said drums, means for feeding fuel to each of said stoker sections through a side wall of the furnace, and means for directing the flow of combustion gases from the said stoker sections laterally through said screens to and over a common path traversing the drums and tubes of the said boiler.
2. A boiler furnace according to claim 1 wherein the boiler comprises upper and lower drums, and wherein further the said combustion gas directing means includes upper and lower baffles extending respectively from the front and rear ends of the combustion chamber transversely over the stoker sections to the said upper and lower drums and forming in effect the top wall of said chamber.
3. A boiler furnace according to claim 2 wherein the upper and lower baffles extend over the upper and under the lower drums respectively and in spaced relation to the latter, the said lower baffle comprising a portion inclined downwardly and rearwardly from the boiler and terminating at the lower end thereof in an ash receiving hopper.
